UNITED STATES PATENT OFFICE.

RALPH B. INGRAM, OF WILKINSBURG, PENNSYLVANIA, ASSIGNOR TO WESTINGHOUSE ELECTRIC & MANUFACTURING COMPANY, A CORPORATION OF PENNSYLVANIA.

LIGHTNING-ARRESTER FOR ELECTRICAL CIRCUITS.

No. 894,150.

Specification of Letters Patent.

Patented July 21, 1908.

Application filed December 4, 1905. Serial No. 290,305.

To all whom it may concern:

Be it known that I, RALPH B. INGRAM, a citizen of the United States, and a resident of Wilkinsburg, in the county of Allegheny and State of Pennsylvania, have invented a new and useful Improvement in Lightning-Arresters for Electrical Circuits, of which the following is a specification.

My invention relates to protective means for electric circuits and it has for its object to provide novel and improved means whereby the dynamo and the other expensive devices of a system may be effectually protected from injuries resulting from lightning or other discharges regardless of the violence thereof.

One form of lightning arrester which has heretofore been employed comprises one or more suitable discharge gaps and a resistance that are arranged in series between the distributing circuit and the ground. The gaps should be adjusted so as to prevent the accumulation upon the circuit of a charge of more than a predetermined potential, and the resistance should ordinarily be so proportioned that only such an amount of current will follow a discharge as may be readily suppressed by the gaps and its proportions should also be such that free discharge may occur therethrough. When the conditions vary to any substantial degree from those for which an arrester is especially adjusted the circuit may not be afforded adequate protection, and I have accordingly provided an arrester comprising a plurality of discharge paths to ground that are adjusted and arranged respectively with reference to each other for charges of different potentials in order that adequate protection may be afforded a circuit with which it is connected.

Figure 1, of the accompanying drawing illustrates diagrammatically a system embodying my invention and Figs. 2, 3, 4, 5 and 6 illustrate modifications of the system shown in Fig. 1.

Arranged in series between a distributing circuit conductor 1 and the ground G are a plurality of discharge gaps 2, 3, 4, 5 and 6 of the well known diverging terminal or "horn" type, the gap 2 being of greater width and consequently of higher striking potential than the others. One terminal of a resistance

7 is connected between the gaps 2 and 3 and the other terminal is connected to the ground G, while connections are made from between adjacent gaps to intermediate points 8, 9 and 10 therein. It may also be advisable to employ a suitable circuit-interrupting device such as a fuse 11 between one terminal of the series of gaps and the ground.

Upon the accumulation of an ordinary charge on the distributing conductor 1, a discharge will occur across the master discharge gap 2 and through all of the resistance 7, the gap 2 serving to protect the circuit from injuries resulting from the charge, while the resistance 7 serves to limit the current in the discharge circuit to such an amount that the arc at the gap may be readily extinguished upon its rising between the terminals and its consequent attenuation. If the charge is of somewhat more than ordinary potential a discharge will also occur across the gap 3 and through the portion of the resistance between the point 8 and the ground. The resistance of this path is so adjusted that the current which follows a discharge across the gaps 2 and 3 may be readily suppressed and the arcs quickly extinguished at the gaps. Since the resistances of the gaps 2 and 3 are now added, that introduced by the device 7 may be less than when the discharge occurs across the gap 2 alone. As the potential of the charge is increased, discharges will occur also across the gaps 4 and 5, and through gradually decreasing amounts of the resistance 7, as will be understood from an inspection of Fig. 1, and the circuit will be adequately protected from injuries resulting from the charge while the currents which will follow the discharges will be suppressed immediately by the resistances. If a charge of extremely high potential accumulates upon the circuit a discharge may occur across the gap 6 through the fuse 11 and directly to the ground, the amount of current which will follow such a discharge being limited by the fuse 11.

The resistance 7 serves not only to limit the amount of current that may follow a discharge, but the portions thereof that are respectively in shunt to the gaps 3, 4 and 5 serve also as paths of comparatively low resistance for the current which would other-

wise follow the discharge across the corresponding gaps, the current being thereby withdrawn from the gaps. This action may occur successively until all of the current is 5 shunted from the several gaps 3, 4 and 5 and the amount of current which passes the unshunted gap 2 will be limited to such as may be readily suppressed thereby.

The mode of operation of the invention is 10 in certain respects similar to that of the arrester forming the subject-matter of patent No. 712,618, granted to the Westinghouse Electric & Manufacturing Company as assignee of Percy H. Thomas.

15 As shown in Fig. 1 the gaps 3, 4, 5 and 6 are of equal width and are consequently of the same striking potential, and they are also of less width than the gap 2, but they may, if desired, be of unequal widths, as indicated at 12, 13, 14 and 15 in Fig. 2, or of progressively increasing or decreasing width. They may also be of the same striking potential as the gap 2, as in Fig. 5 or of greater striking potential, as in Fig. 6, though I prefer that they be of less width, the gap 2 being adjusted for the minimum striking potential at which it is desired to have the arrester operate. Separate resistances 16, 17, 18 and 19 may also be connected between the respective pairs of gaps and the ground, the resistances being of gradually decreasing values as shown in Fig. 2, or they may be equal in amount if desired, as in Fig. 5.

In the protection of high potential circuits 35 I prefer to employ gaps of the "horn" type and to place only one of them between the circuit conductor and the resistance and one between each pair of the connections to the intermediate points thereof, as in Fig. 1, 40 though any other number may be employed. However, when more than one gap is interposed in these portions of the circuit I prefer to employ one or more devices of the character shown and described in Patent No. 492,548, granted to the Westinghouse Electric & Manufacturing Company, as assignee of Alexander J. Wurts, and in Fig. 2 I have shown a system in which such or similar devices are employed. It will be readily understood, that, if it is desired that the striking potential between circuit conductor 20 and terminal 21 of resistance 22 be higher than that between taps 23, 24 and 25 to the resistance, it is only necessary to provide a 50 larger number of gaps in that portion of the circuit, and if it is further desired to provide paths of unequal striking potential in shunt to the several sections of the resistance it is only necessary to provide unequal numbers 55 of such gaps in those paths.

In Fig. 4, separate resistances 26, 27, 28 and 29 are connected from between the various gaps to the ground in a manner similar to what is shown in Fig. 2.

I claim as my invention:

1. The combination with an electric circuit, a plurality of discharge gaps and a circuit-interrupting device, the discharge gaps and the circuit-interrupting device being arranged in series relation between the circuit and the ground, of grounded connections leading from points between the discharge gaps and comprising successively decreasing amounts of ohmic resistance.

2. The combination with an electric circuit, a plurality of discharge gaps and a circuit-interrupting device, the gaps and the circuit-interrupting device being arranged in series relation between the circuit and the ground, of an ohmic resistance one terminal of which is connected to the ground and intermediate points of which are connected to points between the discharge gaps.

3. The combination with an electric circuit, a discharge gap of comparatively high striking potential and a plurality of discharge gaps of lower striking potential arranged in series therewith, of grounded connections from points between the discharge gaps and comprising successively decreasing amounts of resistance.

4. The combination with an electric circuit, a discharge gap of comparatively high striking potential, one or more other discharge gaps of lower striking potential, and a circuit-interrupting device, the discharge gaps and the circuit-interrupting device being arranged in series between the circuit and the ground, of grounded connections from points between the discharge gaps and comprising successively decreasing amounts of resistance.

5. The combination with an electric circuit, a discharge gap of comparatively high striking potential having one terminal connected to the circuit and a resistance connected between the other terminal and the ground, of a series of discharge gaps of approximately equal but lower striking potential than that of the first gap, a circuit-interrupting device whereby the terminal of the series is connected to ground and connections from points between the gaps of said series to intermediate points of the resistance.

6. The combination with an electric circuit, a discharge gap of comparatively high striking potential having one terminal connected to the circuit and a resistance connected between the other terminal and the ground, of a series of discharge gaps of lower striking potential and connections from points between the gaps of said series to intermediate points of the resistance.

7. The combination with an electric circuit, a discharge gap of comparatively high striking potential having one terminal connected to the circuit and a resistance connected between the other terminal and the

- ground, of a series of discharge gaps of approximately equal but lower striking potential than the aforesaid gap and connections from points between the gaps of said 5 series to intermediate points of the resistance.
8. The combination with an electric circuit, a discharge gap of comparatively high striking potential having one terminal connected to the circuit and a resistance connected between the other terminal and the ground, of a series of discharge gaps of approximately equal but lower striking potential than that of the first gap, a circuit interrupting device whereby the terminal of the series is connected to ground and connections from points between the gaps of the series to intermediate points of the resistance.
- 10 9. The combination with an electric circuit, a discharge gap of comparatively high striking potential having one terminal connected to the circuit and a resistance connected between the other terminal and the 15 ground, of one or more other discharge gaps of lower striking potential arranged in series with the first gap and connections from points between the gaps of the series to intermediate points of the resistance.
- 10 10. The combination with an electric circuit, a discharge gap of comparatively high striking potential having one terminal connected to the circuit and a resistance connected between the other terminal and the 20 ground, of one or more other discharge gaps of lower striking potential arranged in series between the first gap and the ground and connections from points between the gaps of the series to intermediate points of the resistance.
- 25 11. The combination with an electric circuit, a plurality of discharge gaps, and a circuit interrupting device, arranged in series between the circuit and the ground, of a 30 plurality of grounded connections leading solely from points between the gaps, and comprising ohmic resistances.
- 35 12. In a protective system for electrical circuits, a plurality of discharge gaps arranged in series between the line to be protected and the ground, and ohmic resistance paths of different values in shunt to different numbers of the gaps, one or more of the gaps being unshunted.
- 40 13. In a protective system for electrical circuits, a plurality of discharge gaps arranged in series between the line to be protected and the ground, and ohmic resistance paths of successively increasing values in shunt to successively increasing numbers of the gaps, one or more of the gaps being unshunted.
- 45 14. In a protective system for electrical circuits, a plurality of discharge gaps arranged in series between the line to be protected and the ground, and a plurality of ohmic resistances of successively increasing values in shunt respectively to successively increasing numbers of the gaps.
- 50 15. In a protective system for electrical circuits, a plurality of discharge gaps arranged in series between the line to be protected and the ground, and a plurality of ohmic resistances of different values in shunt respectively to different numbers of the gaps.
- 55 16. In a protective system for electrical circuits, a plurality of discharge gaps arranged in series between the line to be protected and the ground, and resistance paths of successively increasing values in shunt to portions of the path through the gaps to the ground which have successively increasing striking potentials.
- 60 17. In a protective system for electrical circuits, a plurality of discharge gaps arranged in series between the line to be protected and the ground, and resistance paths of different values in shunt to portions of the path through the gaps to the ground which have different striking potentials.
- 65 18. In a protective system for electrical circuits, a plurality of discharge gaps arranged in series between the line to be protected and the ground, and a plurality of ohmic resistances of different values in shunt respectively, to portions of the path through the gaps to the ground which have different striking potentials.
- 70 19. In a protective system for electrical circuits, a plurality of discharge gaps arranged in series between the line to be protected and the ground, and a plurality of resistances of successively increasing values in shunt, respectively, to portions of the path through the gaps to the ground to successively increasing striking potentials.
- 75 20. The combination with an electric circuit, a plurality of discharge gaps and a circuit-interrupting device arranged in series between the circuit and the ground, of a plurality of grounded connections independent of that through the circuit interrupting device leading solely from points between the gaps and comprising ohmic resistances.
- 80 21. The combination with an electric circuit, and a plurality of discharge gaps arranged in series between the circuit and the ground, of a plurality of grounded connections leading solely from points between the gaps and comprising ohmic resistances.
- 85 22. The combination with an electric circuit, and a plurality of discharge gaps arranged in series between the circuit and the ground, of a plurality of grounded connections leading solely from points between the gaps and comprising ohmic resistances of progressively varying values.
- 90 23. The combination with an electric circuit, and a plurality of discharge gaps arranged in series between the circuit and the ground, of a plurality of grounded connections leading solely from points between the gaps and comprising ohmic resistances of progressively varying values.

ground, of a plurality of grounded connections leading solely from points between the gaps and comprising ohmic resistances that decrease in value as the numbers of gaps between the extremities thereof and the line increase.

In testimony whereof, I have hereunto

subscribed my name this 28th day of November, 1905.

RALPH B. INGRAM.
